SPACEBAND BUFFER FOR LINOTYPE MACHINES

William D. Hahn, Ann Arbor, Mich.

Application May 11, 1938, Serial No. 207,388

5 Claims. (Cl. 199—22)

My invention relates to Linotype machines and more particularly to space band buffers employed therein.

One of the principal objects of my invention is to provide a space band buffer so constructed and arranged to eliminate wear on the buffer caused by impacts of space bands or slugs discharged thereon and at the same time eliminate wear on certain sections of the space bands.

10 Another object of my invention is to provide a device of the above described character so constructed and arranged whereby the same may be readily substituted for buffers already in use on Linotype machines and the like.

15 A further object of my invention is to provide a device of the above described character so constructed and arranged as to not only prevent wear on the buffers but also eliminate the frequent replacement of the buffers.

20 A still further object of my invention is to provide a device of the above described character equipped with a cushioning means or device for receiving the impact of a space band discharged thereon whereby to eliminate wear on the finger 25 of the buffer ordinarily caused by the impact of said band.

Another important object of my invention is to provide a device of the above described character which is simple and durable in construction, 30 reliable in use, efficient in operation, easy of assembly and economical in manufacture.

Other objects and advantages will be apparent from the following description, appended claims and annexed drawing.

35 Referring to the drawing wherein like reference characters designate like parts throughout the several views:

Figure 1 is a side elevation of my invention illustrating the same attached to a section of a 40 Linotype machine of ordinary construction.

Figure 2 is a top plan view of my invention.

Figure 3 is a sectional view taken on the line 3—3 of Figure 2.

Figure 4 is an end elevation thereof.

45 Figure 5 is a side elevation of a buffer of ordinary construction and which my invention replaces for the useful purposes herein set forth.

For the purpose of teaching my invention there is illustrated in Figure 1 of the drawing a section 50 of a Linotype machine of ordinary construction equipped with the usual elevator guides 2 and 3, an assembler 4 having a rear wall 4a, assembler slide 5, assembler elevator 6, star wheel 7 and chute 8.

55 As illustrated in Figure 1 the assembler sup-

ports therein a plurality or a line of matrices 9 between different numbers of which are positioned space bands or slugs 10 and said matrices and space bands are held in contact by a lug 11 on the slide 5 which is tensioned by a spring (not shown). Each of the space bands or quads 10 are fashioned with a notched bottom to receive a horizontally extending guiding member that is attached to and forms part of the Linotype machine. Furthermore, each of the space bands or quads is fashioned with upper laterally extending ears which overlie and engage the walls of the assembler 14.

The guiding member constitutes a buffer and is ordinarily constructed, as illustrated in Figure 5, in the form of an elongated finger F, one end of which is equipped with a bearing B pivoted to the Linotype machine subjacent the slide 5 by means of a screw stud 12.

In operation, when one of the space bands or slugs is discharged from the chute, the lower section of the space band will be impinged upon the finger F adjacent the end thereof which is fashioned with the bearing B. Constant discharging of the space bands onto the finger F, which is 20 of metal construction, causes wear thereon and forms a depression in the upper face thereof as illustrated at W in Figure 5. When the finger F is thus worn the laterally extending ears of the space bands are also subjected to wear because 25 the discharge of the space bands from the chute is checked by the ears engaging the assembler instead of the upper face of the finger F due to the depression W. Furthermore, when the finger F becomes worn it necessitates a replacing thereof 30 by a new finger thereby adding considerably to the cost of operating the machine.

In order to eliminate wear, both on the finger and the laterally extending ears of the space bands and the frequent replacing of buffers, I 40 provide as illustrated in Figures 1 to 4 inclusive a novel form of buffer 15 in lieu of the ordinary type heretofore set forth.

My novel form of buffer 15 comprises a finger 45 16 of an elongated configuration fashioned on one end with laterally extending sections 17 formed with vertically extending walls 18 terminating in upper outwardly flared ends 19, said walls being spaced on each side of the finger 16 50 and thereby forming a yoke for receiving therein the space bands or slugs 10 in a manner to prevent lateral displacement of the latter.

The upper portion of the finger 16 extends 55 above the sections 17 and the end of said upper portion terminates within and adjacent the ends

of the walls 18 to form a vertically extending rim 20 within the yoke as clearly illustrated in Figures 2, 3 and 4 of the drawing. Mounted within the yoke is an elongated cushioning device 5 comprising a member 21 preferably constructed of fiber and fashioned with a longitudinally extending slot 22 through which the rib 20 extends and which serves to form the member 21 with a pair of spaced longitudinally extending arms 23.

The sections 17 of the yoke are provided with a plurality of spaced openings through which are slidably mounted screws 24 threaded into the member 21 on each side of the rib 20. The heads 15 of the screws 24 are disposed subjacent the under face of the sections 17 and serve to limit the upward movement of the member 21. Arranged about the screws 24 and interposed between the lower face of the member 21 and upper faces of the sections 17 are coil springs 25 coacting with the sections 17 and member 21 to urge the member 21 upwardly away from the sections 17. Fashioned on the lower face of one of the sections 17 is a bearing 26 which receives therethrough the stud bolt 12 whereby the buffer 15 is pivotally mounted on the machine 1 subjacent the assembler slide 5 for operation by the elevator 6 in the usual manner.

In use the slugs or space bands are discharged 30 from the chute 8 onto the member 21 adjacent the end of the rib 20 and the impact of the space bands cushion thereon by means of the springs 25. In this position the space bands are moved onto the finger or rib towards the other end of the buffer in the usual manner.

From the foregoing it will be apparent that I 35 have provided a simple and reliable means for eliminating wear on the finger of the buffer and at the same time eliminating the frequent replacing of the buffer with a new one.

As the member 21 becomes worn the same may 40 be readily replaced by removing the screws 24 thereby precluding the necessity of providing an entire new buffer. Furthermore, the member 21, being constructed of fiber and somewhat resilient, is given to a longer life than if the same 45 was constructed of metal or the like.

What I claim is:

1. A device of the character described, comprising, a buffer fashioned with an elongated finger adapted to be adjustably mounted for movement on a Linotype machine subjacent the 50

assembler of the latter, and a spring pressed member mounted on one end of said finger for receiving thereon space bands discharged into said assembler in a manner to receive the impact of said bands to preclude wear on said finger. 5

2. A buffer for Linotype machines and the like comprising an elongated finger fashioned with a yoke at one end and adapted to be adjustably mounted for movement on a Linotype machine subjacent the assembler of the latter, a cushioning device mounted within said yoke for receiving thereon space bands discharged into said assembler in a manner to receive the impact of said bands to preclude wear on said finger. 10

3. A buffer for Linotype machines and the like comprising an elongated finger fashioned with a yoke on one end and adapted to be adjustably mounted for movement on a Linotype machine subjacent the assembler of the latter, a cushioning member mounted within said yoke, and resilient means between said member and said yoke for coaction with said member for cushioning the impact of a slug discharged into said assembler in a manner to preclude engagement of said slug with said finger when discharged on said 20 member. 25

4. A buffer for Linotype machines and the like comprising an elongated finger fashioned with a yoke on one end and a longitudinally extending rib within said yoke, a bearing secured to said yoke for mounting said finger on a Linotype machine subjacent the assembler of the latter, a cushioning member within said yoke and embracing said rib for receiving thereon a space band discharged into said assembler in a manner 30 to receive the impact of said band to preclude wear on said finger, springs interposed between said member and said yoke, and fastening devices securing said member to said yoke and limiting the movement thereof. 35

5. In combination with a device of the character described, of a Linotype machine of that class provided with an assembler in which is positioned matrices and space bands between some of said matrices; and a buffer comprising an elongated finger pivotally mounted on said machine subjacent said assembler, a spring pressed member mounted on one end of said finger for receiving thereon the impact of said space bands discharged into said assembler in a manner to preclude wear on said finger by said impact. 40 45 50
